(57) **CLAIM**

The ornamental design for a sword-shaped toy, as shown and described.

DESCRIPTION

FIG. 1 is a front view of a sword-shaped toy;
FIG. 2 is a rear view thereof;
FIG. 3 is a left side view thereof;
FIG. 4 is a right side view thereof;
FIG. 5 is a top view thereof;
FIG. 6 is a bottom view thereof;
FIG. 7 is a perspective view thereof;
FIG. 8 is another perspective view thereof;
FIG. 9 is a front view of the sword-shaped toy in a transformed state;
FIG. 10 is a rear view of the transformed state thereof;
FIG. 11 is a left side view of the transformed state thereof;
FIG. 12 is a right side view of the transformed state thereof;
FIG. 13 is a top view of the transformed state thereof;
FIG. 14 is a bottom view of the transformed state thereof;
FIG. 15 is a perspective view of the transformed state thereof; and,
FIG. 16 is another perspective view of the transformed state thereof.
The broken lines represent portions of the article that form no part of the claim.
